UNITED STATES PATENT OFFICE

JOHN E. FOWLER, OF ROSSLYN, VIRGINIA

DESIGN FOR A BOTTLE

Application filed April 23, 1931. Serial No. 39,604. Term of patent 14 years.

To all whom it may concern:

Be it known that I, JOHN E. FOWLER, a citizen of the United States, residing at Rosslyn, in the county of Arlington and State of Virginia, have invented a new, original, and ornamental Design for Bottles, of which the following is a specification, reference being had to the accompanying drawings, forming a part thereof.

In the drawings:

Fig. 1 is a side elevational view of a bottle embodying my design.

Fig. 2 is an elevational view looking toward one corner of the bottle.

Fig. 3 is a plan view thereof.

I claim:

The ornamental design for a bottle substantially as shown.

Signed at Rosslyn, in the county of Arlington, and State of Virginia, this 16th day of April, 1931.

JOHN E. FOWLER.
